UNITED STATES PATENT OFFICE.

ELMER T. SPITLER, OF PUEBLO, COLORADO.

MUSIC-LEAF TURNER.

1,134,024.

Specification of Letters Patent. Patented Mar. 30, 1915.

Application filed February 4, 1914. Serial No. 816,448.

To all whom it may concern:

Be it known that I, ELMER T. SPITLER, a citizen of the United States, residing at Pueblo, in the county of Pueblo and State 5 of Colorado, have invented new and useful Improvements in Music-Leaf Turners, of which the following is a specification.

This invention relates to music leaf turners, and the principal object of the invention is to provide a simple and efficient 10 mechanism whereby with a single operating arm any number of sheets of music may be turned in succession from one position to another.

Another object of the invention is the provision of a device of this character, employing 15 a magnetic sheet gripping device carried by a rotatably mounted arm, which is controlled in such manner that the magnet is simultaneously energized with the release of 20 the operating mechanism, which actuates the sheet turning arm upon which the magnet is mounted, and in which the stopping of the operating mechanism automatically acts to 25 produce a demagnetization of the magnet.

Still another object of the invention is the provision of a device of this character, employing 30 a single sheet turning arm for moving the sheet music from one position to another, in which the mechanism is so arranged and controlled that the sheet turning arm will be carried with its attached sheet of music, from one position to another, automatically raised to disengage the sheet, 35 and then automatically returned to its initial position for engagement with the second sheet.

Further objects of the invention will appear 40 as the following specific description is read in connection with the accompanying drawings, which form a part of this application, and in which:

Figure 1 is a front elevation showing the device mounted upon a music rack, and 45 showing the circuit in diagram. Fig. 2 is a top plan view thereof. Fig. 3 is a view similar to Fig. 1, with the front of the case removed, so as to show the operating parts in elevation. Fig. 4 is a detail horizontal 50 sectional view taken on a line 4—4 of Fig. 3. Fig. 5 is a perspective view of the driving gear. Fig. 6 is a detail vertical section on the line 6—6 of Fig. 3. Fig. 7 is a similar view through one of the music sheet disks.

Referring more particularly to the drawings, 55 1 represents a suitable casing which

may be of any desired shape adapted for the purpose, and which has journaled therein a vertically positioned shaft 3, having adjustably mounted on its upper end a sheet turning arm 4. This sheet turning arm is constructed in two parts, 5 and 6, the former being tubular and having a collar 6' at one end to surround the shaft 3, and to receive the set screw 7 by which the arm may be held in 60 adjusted position. The outer portion of the arm 4 is adjustably arranged within the tubular part 5 and is held in adjusted position by a set screw 8. The outer member of the arm 6 carries the transverse tube or 65 sleeve 9, in which is slidably mounted a supporting rod 10, carrying upon its lower end an electromagnet 11. The rod 10 is held in adjusted position in the sleeve by a set screw 12, and the circuit of the magnet to 70 the battery is indicated by wires by the numerals 13 and 14.

The shaft 3 has keyed thereto a segmental gear 15, which is arranged to be engaged by a similar gear 16 secured to the upper 80 end of the driving shaft 17. This driving shaft is driven by an ordinary spring motor 18, which needs no description, but is wound up in the usual manner by the key 19, projecting through the bottom of the casing 1. 85

The gear 16 has integrally formed therewith a segmental collar 20, which has one of its shouldered terminals 21 arranged to be engaged by a pin 22, pivotally mounted at its lower end upon the switch lever 23 and 90 normally raised into operative position by a spring 24, which surrounds the pin and is connected thereto at its lower end, and at its upper end to the bearing 25, through which the pin slides.

The switch lever 23 is pivotally mounted upon a bracket 26 secured to the inner side of the casing, and has its free end arranged to engage a contact terminal 27, which is connected to the wire 13 of the battery circuit, the switch lever being connected to the same wire leading to one side of the battery, and the other wire 14 leading to the opposite side of the battery.

The switch lever is operated and the pin 105 22 withdrawn from engagement with the shoulder 21 by a connecting rod 28, which is connected to the switch lever at one end, and at the opposite end to an operating lever 29, pivoted to a bracket 30 upon the 110 underside of the casing, and having a finger piece 31 at its outer end.

In order that the magnet 11 and its associate parts may be lifted from beneath the sheet after turning, the section 5 of the arm 4 is pivoted to the collar 6, as shown at 32, 5 so that when the outer end of the arm 4 rides over the inclined portion 33 on the standard 34 the magnet will be lifted. It will be more clearly understood hereinafter that prior to the lifting of the magnet the same 10 will be deenergized to avoid lifting of the sheet, and that immediately after lifting, the arm is returned to initial position, in order to engage another sheet. This return of the arm 4 to initial position is accomplished by 15 a spring 35 surrounding the shaft 3, and connected at one end thereto and at the opposite end to the casing.

Each music sheet 36 is supplied with a metallic disk 36' which is insulated from the sheet by a disk of mica or other suitable insulation. All these disks are so positioned upon the sheet that they will be within the range of adjustment of the magnet.

The casing 1 is preferably mounted upon 25 the back of a sheet supporting board 39, and this board may carry, if desired, suitable music clamping mechanism, which will hold the music in its center, and, yet, permit pivoting of the sheet. The board may also 30 carry the batteries, if found to be desirable.

In the operation of the device the arms 5 and 6 and the rod 10 are adjusted so as to bring the magnet 11 in contact with a disk 36' on the first sheet of music. When it is 35 desired to turn the sheet the lever 29 is operated to bring the sweep lever into engagement with the terminal contact 27. Simultaneously with the completion of the battery circuit or immediately succeeding 40 the same, the pin 22 is withdrawn, from engagement with the shoulder 21, against the tension of the spring 24. The spring motor 18 now acts to rotate the shaft 17, thus causing the gear 16 to mesh with the driving 45 gear 15 for a predetermined distance. When the toothed section of the gear 16 acts, the shaft 17 turns until the collar 20 releases the pin 22 which it has held down previously. Upon the release of the pin the spring 24 50 will act to project the same into the path of the shoulder 21, and will simultaneously disconnect the switch lever 23 from contact 27. Prior to the engagement of the shoulder 21 with the pin 22, but after the release of the 55 switch arm from the contact 27, the arm 4 will be brought into engagement with and ride upon the inclined portion 33 on the standard 34, thus lifting the magnet from engagement with the disk after it has been 60 deenergized. Also prior to the engagement of the shoulder 21 with the pin 22 the toothed portion of the gear 16 will be disengaged from the toothed portion of the gear 15 and

the spring 35 allowed to return the arm to its initial position, thereby bringing the 65 magnet into engagement with the disk on the second sheet to be turned.

I claim—

1. In a music leaf turner, a rotatably mounted sheet turning arm, means normally tending to actuate the same for turning a sheet of music from one position to another, means for holding the actuating means in inoperative position, means for connecting the arm with a sheet of music, means for successively actuating the connecting means and releasing said holding means, and means for turning the sheet turning arm to normal position.

2. In a music leaf turner, a rotatably mounted sheet turning arm, means normally tending to actuate the sheet turning arm to turn a sheet of music from one position to another, means for connecting said arm with a sheet of music, means for holding the actuating means in inoperative position, means for successively actuating the connecting means and releasing the said holding means, means for maintaining the connecting means in operative position, and means for successively throwing the holding means into operative position and rendering the connecting means inoperative.

3. In a music leaf turner, a rotatably mounted sheet turning arm, means normally tending to actuate the sheet turning arm to turn a sheet of music from one position to another, means for connecting said arm with a sheet of music, means for holding the actuating means in inoperative position, means for successively actuating the connecting means and releasing the said holding means, means for maintaining the connecting means in operative position, means for successively throwing the holding means into operative 105 position and rendering the connecting means inoperative, and means for returning the sheet turning arm to normal position.

4. In combination with a sheet of music, having a magnetic armature thereon, together with mechanical means including a sheet turning arm, carrying a magnet, means for energizing and deenergizing the same in different positions in the sheet turning arm, mechanical means for lifting the magnet out 115 of engagement with the armature after the same has been deenergized, and means for returning the sheet turning arm to initial position.

In testimony whereof I affix my signature 120 in presence of two witnesses.

ELMER T. SPITLER.
